US00D447126B1

(12) **United States Design Patent**
Carvalho

(10) Patent No.: **US D447,126 S**
(45) Date of Patent: **** Aug. 28, 2001**

(54) **CELLULAR CORDLESS TELEPHONE**

(75) Inventor: **David Carvalho**, Sartrouville (FR)

(73) Assignee: **U.S. Philips Corporation**, New York,
NY (US)

(**) Term: **14 Years**

(21) Appl. No.: **29/127,626**

(22) Filed: **Aug. 9, 2000**

(30) **Foreign Application Priority Data**

Feb. 24, 2000 (XH) DMA/004 802

(51) LOC (7) Cl. **14-03**

(52) U.S. Cl. **D14/138**
